DESIGN FOR A SUPPORT.

55,796.

Specification for Design.

Patented July 13, 1920.

Application filed April 16, 1920. Serial No. 374,480. Term of patent 7 years.

To all whom it may concern:

Be it known that I, HENRY KAPNECK, a citizen of the United States, residing at Washington, in the District of Columbia, have invented a new, original, and ornamental Design for Supports, of which the following is a specification, reference being had to the accompanying drawing, forming part thereof.

In the drawings,

Figure 1 is a face view of the support, and
Fig. 2 is a side view thereof.

The support is primarily for electric light fixtures. The lower stem portion may be fastened to a wall pan or suspended pan and the electric socket may be suspended from an ordinary socket supporting element such as a ring emerging from the mouth of the the animal's head, which as shown in the drawings, is a lion's head.

I claim:

The ornamental design for a support, as shown.

HENRY KAPNECK.
